(57) **CLAIM**

The ornamental design for a maglev soap holder, as shown and described.

DESCRIPTION

FIG. 1 is a front elevation view of a maglev soap holder of my new design;

FIG. 2 is a top plan view thereof;

FIG. 3 is a bottom plan view thereof;

FIG. 4 is a left side view thereof;

FIG. 5 is a right side view thereof;

FIG. 6 is a perspective view thereof;

FIG. 7 is a rear elevation view thereof; and,

FIG. 8 is a perspective view in a use state thereof.

The broken lines are for illustrative purposes only and form no part of the claimed design.
